UNITED STATES PATENT OFFICE.

PARKER C. DYKES, OF SAN FRANCISCO, CALIFORNIA, ASSIGNOR TO DYKES, INCORPORATED, OF SAN FRANCISCO, CALIFORNIA, A CORPORATION OF CALIFORNIA.

FIRE-TUBE BOILER.

Application filed April 8, 1925. Serial No. 21,708.

The present invention relates to improvements in steam boilers and has particular reference to the type of steam boiler for use in connection with motor vehicles and the like.

The general object of the invention is to increase the efficiency of the present type of fire tube boiler by adapting the same to produce superheated steam of a higher temperature than has been heretofore had; to the end that the power efficiency of the motor will be increased because of the resistance to condensation on the part of the high temperature steam within the cylinder.

The above and other objects are accomplished by instrumentalities pointed out in the following specification.

The invention is clearly defined in the claims.

A satisfactory embodiment of the invention is illustrated in the accompanying drawings forming part of the specification and in which—

Figure 1 is a sectional plan taken through the upper portion of the jacket and with the steam dome removed.

Figure 2 is a vertical cross section of the invention.

Figure 3 is a detail plan with the steam dome removed but showing the sectional or intermediate superheater.

Figure 4 is a detail side elevation of the invention.

Figure 5 is a top plan view of Figure 4.

Figure 6 is a bottom plan view.

Figure 7 is a detail plan of one of the circulating or generating tubes.

Figure 8 is a side elevation of Figure 7.

Figure 9 is a detail plan of the main superheater.

Figure 10 is a detail vertical cross section taken on the line 10—10 of Figure 9, looking in the direction of the arrow.

Figure 11 is a view similar to Figure 10, but taken on the line 11—11 of Figure 9, looking in the direction of the arrow.

Figure 12 is a detail plan of the intermediate superheater.

Figure 13 is a side elevation of Figure 12, and

Figure 14 is a detail side elevation of the coupling between the conduit connecting the water leg and the steam dome.

The device of this invention consists essentially of a shell *a* constituting the body of the boiler, a jacket *b* surrounding the shell and formed of heat insulating material such as an asbestos core *5* disposed between inner and outer plates *6* and *7*. The body of the shell *a* is disposed over a burner constituting a furnace (not shown) which extends into a fire chamber indicated by *8*. In the embodiment shown in Figures 1, 2 and 4, the bulk of the device is such as will permit of the arrangement of the same underneath the hood of a motor vehicle, in which position the device will be supported by a suitable bed frame (not shown) and secured thereto in any well known or preferred manner. The shell *a* is provided with a relatively large number of lateral and vertical flues respectively indicated by *9* and *10*. These flues place the interior of the shell in communication with the surrounding space *c* underneath the jacket *b*, which space *c* communicates with an outlet pipe *11* through which the products of combustion rising from the burner and passing through the flues and into the space *c* escape into the atmosphere.

The shell *a* includes in its construction a water leg *12* which extends completely around the shell and around the flues *9*. The top or cover of the shell constitutes a steam dome *13* through which pass the flues *10*. A flange or skirt *14* supports the dome *13* upon the upper end wall of the water leg *12*. Within the shell *a* are disposed two vertical columns *d* and *e* of spiral tubes *15*. The component tubes of each column are separated one from the other and arranged one above the other as most clearly shown in Figure 2. The inner ends of the spirals are connected to the lower portion of the water leg *12*. This construction is most clearly shown in Figures 2 and 6 where it will be noted that the lower ends of the tubes *15* are connected in a common horizontal plane to the lower portion of the water leg *12*. As shown in Figure 1, the outer ends of the tubes as indicated by *16* are connected into the water leg along spaced vertical points disposed in the horizontal planes of the coils so that the opposite ends of each coil are connected to spaced vertical portions of the water leg *12*. As clearly shown in Figures 4 and 5, tubular connections *17* extend from

the upper end of the leg into the base of the steam dome 13. With this construction, circulation through the tubes and water leg is effected and passage afforded for the 5 steam into the steam dome 13. A superheater comprising an evolute pipe coil 18 and an involute pipe coil 19 is disposed between the upper ends of the columns *d* and *e* and the base 20 of the steam dome 13, the coils 10 18 and 19 being continuations one of the other. The inner end of coil 18 is directed upwardly through the dome as indicated by 21 in Figure 2, and exteriorly of the dome a transversely disposed connection 22 connects the end portion 21 with a perforated 15 tubular extension 23 which is directed downwardly through the top 24 and into the central space of the dome as clearly shown in Figures 2, 3 and 5. The inner end portion 26 of the coil 19 is directed downwardly and outwardly and through the flange 14 to the exterior of the shell where it is directed into the lateral port of the casing 25 of the throttle valve. A tubular 20 connection 27 extends from one end of the throttle valve casing 25. The throttle stem 28' which extends into the casing 25 of the throttle valve operates the valve within the casing to control communication between the tubular portions 26 and 27. The tubular portion 27 is directed inwardly through the flange 14 and into a vertically disposed chamber 28 extending vertically downward through one side of the space 25 between the columns *d* and *e* and into the fire box 8. A tubular conduit 29 forms an extension of tube 27 and is disposed within the chamber 28 and is proportioned with respect to the chamber 28 so that an annular 30 passage 30 is provided within the chamber, which passage extends by virtue of the length of the conduit 29 to a point adjacent to the lower end of the chamber. A tubular extension 31 extends into the upper end 40 of a chamber 32 which is disposed adjacent to the chamber 28. A tubular inlet 32' is connected to the extension 31 and extends to the lower end portion of chamber 32. A coupling 33' extends diagonally across the 45 space between the columns *d* and *e* to the opposite side of the shell, at which point it enters a chamber 33 similar to chamber 28 and in which is disposed an inlet tube 34 similar to the tube 29. The tube 34 extends to the lower end portion of the chamber 33 50 and is connected at its upper end to the extension 33'. This tube operates to provide an annular passage similar to the passages described in connection with chambers 28 and 31. An outlet tube 35 extends from the upper end portion of chamber 33 into an adjacent chamber 36 which extends together with the chamber 33 downwardly and into the fire box 8. The interior of the chamber 60 36 corresponds to chamber 31. The outlet tube 37 which corresponds to outlet tube 32 extends outwardly and through the shell and to the steam motor. From the foregoing it is clear that the chambers 28, 31, 33 and 36 by virtue of their construction 70 and arrangement operate as superheaters. In the use of the device the height of the water column in the water leg 12 will correspond approximately to one-half the height of the said water leg so that the tubes 75 disposed below the level of the water column will function as circulating tubes, while those above will act as generating tubes. When steam is generated in either of the columns *d* and *e* it passes through the generating tubes and then into the water leg 12. At this time the steam is saturated. From the water leg 12 the steam passes through the tubular connections 17 and into the dome 13 where its temperature is raised by the 80 heat of the chamber had from exposure of the base 20 thereof to the heat of the furnace. From the dome 13 the steam passes through the perforated extension 23, connection 22 and extension 21 into the evolute 85 coil 18 of the second or intermediate superheater. On account of the location of the said intermediate superheater, the temperature of the steam is increased beyond the 90 temperature received in the dome 13. Owing to the construction of the coils 18 and 19, considerable time is required for the steam to pass through the said coils and finally to the throttle valve. When the last 95 named member is opened, the steam passes through the extension 26 into the extension 27 and into the first chamber 28. By virtue of the tube 29 the steam is conveyed downwardly and to the hottest portion of chamber 28 from which it rises through the annular space 30 and passes through the extension 31 and into the chamber 33 through the inlet tube 32'. In that the construction 100 of chamber 32 corresponds with that of chamber 28, the steam is required to follow a corresponding course until it emerges through the coupling 33' which conveys the steam to the chamber 33 from which the steam passes into the chamber 36 and then 105 into the main steam pipe 37 and then to the motor, not shown. Thus it is seen that upon opening the throttle, the superheated steam from the intermediate superheater made up of the coils 18 and 19 is subjected to a further superheating before leaving the boiler 110 on its way to the motor. The final superheating step accomplished by the chambers 28, 32, 33 and 36 increases the temperature 115 of the steam to the maximum within the heating limit of the furnace or burner within the fire box, and this because of the construction and location of the said chambers. Thus it will be seen that the steam upon moving through the main steam pipe 37 is thoroughly dried and at a temperature that will 120 125 130

prevent condensation in the cylinder of the motor prior to performing work in connection with the pistons.

In Figure 14 I have shown a preferred form of connection between the tubes 17 and the upper end of the water leg 13. In this connection the outer end portion of each of the tubes 17 is directed into an angular coupling 38 which has a tapered lower end portion 39 directed into a correspondingly shaped opening in a piece of relatively soft metal 40, such as brass, which is first inserted into an opening in the upper end wall 41 of the water leg and then expanded so as to interlock with the screw threaded wall of the opening. In this way an effective tight joint is had in that under the action of heat the soft metal 40 will tend to expand to a greater extent than the relatively hard steel forming the top wall 41 of the water leg. The fitting is locked by a tapered screw 42 which is screwed into a correspondingly shaped opening in the top wall 31 and passes through an opening in the lateral extension 43 on the body of the fitting which is clamped by a nut 44 which is screwed upon the screw 42.

Referring now to Figure 1, it will be noted that spreaders 45 are disposed within the columns *d* and *e* for the purpose of deflecting and spreading the flame of the furnace laterally around the tubes 15.

Although I have shown and described an ideal embodiment of my invention, I wish to have it understood that the same is susceptible of certain changes, and I reserve the right to employ such as may come within the scope of the appended claims.

I claim:

1. In a fire tube boiler, a shell, a vertical water leg arranged within the shell, a steam dome forming a closure for one end of the shell, a column comprising a plurality of tubes disposed within the shell and above the fire box and connected to the water leg and the steam dome, a superheating coil disposed between the column and the steam dome and a steam chamber extending downwardly and into the firebox and connected to the superheating coil.

2. In a fire tube boiler, a shell, a vertical water leg arranged within the shell, a steam dome forming a closure for one end of the shell, a column comprising a plurality of tubes disposed within the shell and above the fire box and connected to the water leg and the steam dome, a superheating coil disposed between the column and the steam dome, a plurality of steam chambers extending downwardly into the fire box and connected one to the other, and a valve controlled connection between the said steam chambers and the superheating coil.

PARKER C. DYKES.
